(57) **CLAIM**

I claim the ornamental design for the two-sided putter, as shown and described.

DESCRIPTION

FIG. 1 is a perspective view of the two-sided putter.

FIG. 2 is a front elevational view of the two-sided putter; the undisclosed opposite side being identical.

FIG. 3 is the top view of the two-sided putter.

FIG. 4 is the bottom view of the two-sided putter; and,

FIG. 5 is an end view of the two-sided putter.

The broken line showing of the fragmented shaft on FIG. 1 is included for the purpose of illustrating and forms no part of the claimed design.
